UNITED STATES PATENT OFFICE

2,551,766

COMBINATION COFFEE AND CARD TABLE

Robert W. Service, Hamilton, Ohio

Application March 26, 1947, Serial No. 737,263

2 Claims. (Cl. 311—108)

1

This invention relates to new and useful improvements in combination tables and more particularly to a combination coffee and card table.

The primary feature of the present invention is to provide a device of the character referred to comprising a card table which may conveniently be transferred into a coffee table.

A further feature of the present invention is to provide a combination table including a removable base portion which when removed therefrom transforms the original table into a lower table for use as a coffee table.

A still further feature of the present invention is to provide a device of the class described that is simple and practical in construction, neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view showing the combination table construction in accordance with the present invention;

Figure 2 is a front elevational view of the upper portion of the combination table forming a hassock;

Figure 3 is a front elevational view of the lower portion of the combination table forming a hassock;

Figure 4 is a sectional view taken on a line 4—4 of Figure 2;

Figure 5 is a side elevational view of the combination table in complete form;

Figure 6 is an enlarged top plan view of Figure 3, the hassock top removed therefrom;

Figure 7 is an enlarged side elevational view of the hassock top;

Figure 8 is a side elevational view of the hassock base, the side wall covering removed therefrom;

Figure 9 is an enlarged fragmentary sectional view taken on line 9—9 of Figure 1;

Figure 10 is an enlarged sectional view taken on line 10—10 of Figure 6; and

Figure 11 is a sectional view taken on a line 11—11 of Figure 4.

Referring now to the drawings in detail, where-
in for the purpose of illustration, I have disclosed a preferred embodiment of the present invention, the numeral 5 represents generally a fixed table base including a pair of preferably circular upper and lower rings 6 and 7 formed

2

of arcuate sections connected at their abutting edges by arcuate braces 8. This pair of rings 6 and 7 are spaced apart and retained in horizontal parallelism by uprights 9.

Suitably secured to the upper ring is a preferably circular table top designated generally by the numeral 10 said top comprising a circular horizontally positioned rim 11 on which a preferably wooden disc 12 of slightly smaller diameter is suitably secured and said disc 12 is covered by a similar size disc 13 of veneer or any suitable material that will give the desired color and attractiveness for the table top, thus covering the disc 12.

15 A usual molding strip 14 of circular form is secured on rim 11 to bear against the outer edges of the disc 12 and disc 13 and said strip 14 is preferably of enameled or stained polished wood.

Completely encircling the outer edges of rings 6 and 7 is a circumferential side wall 15 of linoleum or any other suitable material.

The numeral 16 designates generally a hassock body which forms the removable base for the combination table.

25 The hassock is composed of an upper ring 17 and lower ring 18 formed of arcuate sections 19 and 20 respectively which are connected at their abutting edges by arcuate braces 21. The arcuate sections 20 forming the lower ring 18 are of 30 slightly larger width than the arcuate sections 19 of the upper ring to provide a shoulder 22 on which is secured the outer edge of a circular bottom 23.

The rings 17 and 18 are held spaced apart 35 in horizontal parallelism by uprights 24.

Secured by fastening means 25 to the inner vertical edges of uprights 24 are the lower ends of preferably wooden cleats 26 whose upper ends project upwardly from ring 17 slightly, as shown best in Figure 10.

A circumferential side wall 27 of linoleum or any other suitable material encircles the outer edges of rings 17 and 18 and is suitably secured thereto.

45 The removable top for the hassock designated generally by the numeral 29 comprises a disc 30 having a downwardly extending flanged portion 31.

The disc 30 and flanged portion 31 are covered 50 with leather or any other attractive upholstering material 32, tacked or otherwise suitably secured to the flanged portion 31 with padding between disc 30 and the upholstery (not shown). The upholstered cushion might be finished by tufting, as shown in Figure 3 of the drawings, or left smooth.

Cleats 33 suitably secured to disc 30 project downwardly from the disc 30 past the flanged portion 31 and are spaced inwardly from the flanged portion. Said cleats are adapted to tightly fit between the inner edge of the upper ring 17 of the hassock and said cleats 26 secured to uprights 24 are adapted to tightly fit against the inner edge of the flanged portion 31.

The top 29 in this manner is easily removed from the hassock so that articles may be conveniently stored in the body of the hassock for easy accessibility.

The table, as shown in Figure 5, is made up by removing the hassock top 29 and placing the fixed base 5 on the hassock body 16 so that the cleats 26 of the hassock body fit tightly against the inner edge of the lower ring 7 of said fixed base whereby the table is relatively high and may be used as a card table or the like.

When the hassock body is removed from base 5, the table is of slightly decreased height as shown in Figure 2, and in this form may be used as a coffee table or the like, and by placing the hassock top 29 on the hassock body as shown in Figure 3, two articles are formed from one.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims. The converting method applied to this combination is definitely not confined to the round design used in the drawings, since this converting method can be applied to a square, rectangular, hexagonal, octagonal or any other suitable shape or design of table. And the sections of base required to raise the table to card table height is not confined in the construction of the hassock

alone, because it might be harbored in many other ways such as the construction of an end table, or be rendered useful in the construction of some other small piece of furniture, or it might be just held in storage until needed.

What I claim is:

1. In an article of the class described, a hollow cylindrical base including an upper ring and a lower ring, uprights connecting the rings, said uprights having outer edges flush with the outer edges of said rings, a bottom wall carried by the lower ring, a circumferential side wall between the outer edges of the rings and the outer edges of the uprights, a removable top including an annular member supported on the upper ring of the base, and upstanding cleat means carried by the uprights and engaging the inner edge of the upper ring, said cleat means having portions projecting upwardly from the upper ring to engage 10 the annular member and holding the latter against horizontal movement on the base.
2. In a coffee table including a top and an upright fixed to the top and forming a support for the top, means for supporting the upright and 25 the top in an elevated position for use of the same as a card table, said means comprising a base of a length less than the length of said upright, and cleat means between the base and the upright, said cleat means including a plurality 30 of circumferentially spaced upstanding lugs carried by said base and having portions projecting upwardly from the upper end of said base for engaging the upright.

ROBERT W. SERVICE.
